UNITED STATES PATENT OFFICE.

EVERETT E. DUNHAM, OF SEATTLE, WASHINGTON.

CLAMPING-BOLT.

1,269,912.

Specification of Letters Patent. Patented June 18, 1918.

Application filed January 17, 1918. Serial No. 212,358.

To all whom it may concern:

Be it known that I, EVERETT E. DUNHAM, citizen of the United States, residing at Seattle, in the county of King and State of Washington, have invented a certain new and useful Improvement in Clamping-Bolts, of which the following is a specification.

My invention relates to improvements in clamping bolts, and the object of my invention is to provide a clamping bolt which shall be adapted to clamp an object temporarily against one side of a plate of metal, as, for instance, to one side of a metal plate comprising a part of the wall of the hull 15 of an iron ship in the process of building such ship, and which bolt shall embody such features as will adapt it to be disposed in its operative position to extend through said plate and through the object to be clamped thereto, by one workmen located on one side 20 of said plate, without the aid of any other workman located on the other side of said plate.

I accomplish this object by devices illustrated in the accompanying drawings, wherein—

Figure 1 is a view in elevation of one side of a clamping bolt embodying my invention which view shows an operative part in elevation of one of its broader sides;

Fig. 2 is a view of the same in elevation of another side, which view shows the same operative part in elevation of one of its narrower sides; and

Fig. 3 is a view of the same in cross-section on broken line 3, 3 of Fig. 2.

Referring to the drawings, wherein like numerals indicate like parts, 4 is a metal bolt of circular cross-section, one portion of which is provided with a screw-thread 5, upon which may be operatively disposed a well known form of a clamping nut, not shown, and terminates in an end portion 15 that is square in cross-section whereby it is adapted to be engaged by a wrench, and whose other end portion is bifurcated by a slot 6 that extends longitudinally to terminate at a point not far distant from the inner end of the screw-thread 5 as shown more clearly in Fig. 2.

A clamping bar 7, of rectangular form in cross-section, is freely disposed in the slot 6 where it is pivotally mounted on a pivot 8 that extends through its central portion and through the opposite members of the bifurcated portion of the bolt 4, which pivot 8

is shown by a circular line in Fig. 1 and indicated by parallel dotted lines in Fig. 2, and whereon said clamping bar 7 may be swung from its position shown by full lines 60 in Figs. 1 and 2 to a position at right angles to the axis of the bolt 4 as indicated by lines formed by dots and dashes in Fig. 1.

The clamping bar 7 has one of its end portions bifurcated by a narrow slot 9 that 65 extends to a point near the pivot 8 as shown by full lines in Fig. 2, and as indicated by the line 10 formed by dots and by another line 11 formed by dots and dashes in Fig. 1.

Extending through the members of the 70 bifurcated portion of the clamping bar 7, at a point near the inner end of the slot 9 and near one of its edges, is a pin 12 indicated by parallel dotted lines in Fig. 2, the same pin 12 being indicated at each of two 75 different operative positions by a circular dotted line in Fig. 1.

Articulated to the pin 12 within the slot 9 is one end of a stiff but springy actuating wire rod 13 that projects from said slot 9 80 and extends thence through a longitudinal hole 14 that extends from the inner end of the slot 6 through and out of the screw-threaded end portion of bolt 4 to a point distant therefrom, which wire rod 13 may 85 be manipulated to move in endwise directions to swing the clamping bar 7 to and from its position shown by full lines in Figs. 1 and 2 and its position shown by lines formed by dots and dashes in Fig. 1. 90

To utilize a clamping bolt embodying my invention in the manner hereinbefore described, the clamping bar 7 is disposed parallel with the axis of the bolt 4 in the position indicated by Fig. 2, and the workman, 95 being located on that side of a plate to which an object is to be clamped, inserts the clamping member 7 and the adjacent end portion of the bolt 4 through a hole in said object and through a hole that extends 100 through the plate, to which the object is to be clamped, for such distance that the inner end of the clamping bar 7 will pass beyond the other side of said plate and thereupon the wire 13 is pushed inwardly to 105 swing the clamping bar 7 into a position that is at right angles to the bolt 4 whereupon the bolt 4 is pulled back until the adjacent edge portion of the clamping bar 7 rests against the surface of the other side of said plate 110 and thereupon a nut is screwed on to the screw-threads 5 and forced against the outer

surface of the object to be clamped securely to hold said object in its required position.

During the operation of screwing the nut on the screw-threads 5 the bolt may be prevented from turning by applying a suitable tool, as another wrench, to the squared end portion 5, which will project outwardly from the nut.

When it is desired to remove the object from the side of a plate the nut is removed from the screw-threaded portion of the bolt and thereupon the bolt is pushed inwardly for a distance to permit the clamping bar 7 to be swung into its position parallel with the axis of the bolt in response to pulling the wire rod 13 outwardly and with the clamping bar 7 in such position the bolt may be wholly withdrawn to release the object clamped.

20. What I claim is:

A clamping bolt of the class described one portion of which is provided with a screw-thread and another portion of which is bifurcated by a slot that extends from one

of its ends to a point near the inner end 25 of said screw-thread, said bolt being provided with a hole that extends longitudinally from the inner end of said slot throughout the remainder of its length; a clamping bar pivotally mounted in the slot 30 between the members of the bifurcated portion of said cylindrical portion, said clamping bar being provided with a slot that extends in a plane parallel with its broader sides from one of its ends to a point near its 35 pivot; and a wire rod having one of its ends articulated with said clamping bar at a point within the slot thereof and disposed to extend from said point through said longitudinal disposed hole for a distance beyond 40 the outer end thereof to adapt it to be manipulated to move in endwise directions to cause said clamping bar to swing on its pivot to different angular positions.

In witness whereof, I hereunto subscribe 45 my name this 6th day of January, A. D., 1918.

EVERETT E. DUNHAM.
